UNITED STATES PATENT OFFICE

137,341

DESIGN FOR A BADGE

Eduard Muehsam, Staten Island, N. Y.

Application December 24, 1942, Serial No. 109,127

Term of patent 3½ years

To all whom it may concern:

Be it known that I, Eduard Muehsam, a citizen of no country, residing at Staten Island, N. Y., in the county of New York and State of New York, have invented a new, original, and ornamental Design for a Badge, of which the following is a specification, reference being had to the accompanying drawing, forming part thereof.

In the drawing the figure is a perspective view of a badge, showing my new design.

I claim:

The ornamental design for a badge, as shown.

EDUARD MUEHSAM.
